John J. Machacek
By Victor J. Evans & Co.
Attorney.*

UNITED STATES PATENT OFFICE

JOHN J. MACHACEK, OF WESTON, NEBRASKA, ASSIGNOR OF ONE-HALF TO JOSEPH EGR,
OF VALPARAISO, NEBRASKA

ALARM FOR INCUBATORS OR BROODERS

Application filed April 4, 1931. Serial No. 527,837.

This invention relates to alarms especially adaptable for incubators, brooders and the like and has for the primary object, the provision of a thermostatically controlled switch adapted to automatically close an electric circuit to the alarm when the temperature in an incubator or brooder rises or falls below a predetermined temperature, so that the attendant will be warned in sufficient time to prevent injury to chickens from either excessive or from too low a temperature, thereby allowing the attendant to be free for other work or for sleep at nighttime and until such time the incubator or brooder needs attention.

Another object of this invention is the provision of an alarm for the incubator or brooder of the above stated character which will be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawing, in which

The figure is a perspective view illustrating an alarm for an incubator or brooder constructed in accordance with my invention.

Referring in detail to the drawing, the numeral 1 indicates a base of elongated formation preferably constructed of metal or any other material suitable to provide a conductor for electricity and still have the desired rigidity for supporting the device. The base 1 is bent intermediate its ends to form a substantially inverted V-shaped pivoted supporting portion 2 and which is slotted inwardly from the apex portion as shown at 3 to provide spaced bearing portions 4 receiving a pivot pin 6 on which is journaled a thermostat bar or arm 7. The bar or arm 7 is pivotally mounted intermediate its ends and has one end disposed between vertical guide members 8 formed integral with one end of the base while the other end of the

bar or arm 7 extends between the arm portions 9 of a substantially U-shaped contact member 10. The contact 10 forms an integral construction with one end of the base 1 and the arm portions 9 thereof are provided with screw-threaded openings to receive screw-threaded contact poles 11 which may be adjusted toward and from each other and relative to the arm portions 9 as desired. A thermostatic disk 12 is mounted on the base 1 as shown at 13 and carries relatively spaced guide members 14 which receive therebetween the bar or arm 7. The guide members 14 are connected by a stop member 15 adapted to be engaged by the bar or arm 7 under the influence of an expansion spring 16 interposed between the base and the bar or arm 7. A movable contact pole 17 is mounted in the insulating sleeve 18 carried by the bar or arm 7 for the purpose of connecting either of the contact poles 11 depending in which direction the thermostatic disk 12 moves the bar or arm 7.

An electrical alarm 19 is connected to the movable contact pole 17 by a conductor 20 and is also connected to a battery or other electrical source 21 by a conductor 22. A conductor 23 connects the battery or electrical source 21 to one of the contact poles 11.

It is to be understood that the base 1 is mounted or located in any suitable manner within a brooder or incubator that the disk 12 will be affected by the temperature within the incubator or brooder, while the alarm 19 may be located at any desired place such as in the sleeping quarters of the attendant. Should the temperature in the incubator or brooder rise or fall below a predetermined degree, the bar or arm 7 will be rocked on its pivot 6 by the thermostatic disk 12 engaging either of the contact poles 11 by the movable contact pole 17 completing an electrical circuit to the alarm, consequently indicating to the attendant that the temperature within the incubator or brooder either has raised or lowered beyond a predetermined degree, therefore his attention is necessary for regulating the heating plant of the brooder or incubator that the temperature may be again brought to the desired degree.

While I have shown and described the preferred embodiment of my invention, it will be understood that minor changes in construction, combination and arrangement of parts may be made without departing from the spirit and scope of the invention as claimed.

Having thus described my invention, what I claim is:

- 10 A temperature control switch comprising an elongated base of electrical conductive material having its intermediate portion offset in V-shape and slotted and apertured to provide spaced bearings disposed in a plane
- 15 above the base, a pivot in said bearings and extending across the slotted portion of the V-shaped offset, an arm extending parallel with the base and apertured intermediate its ends to receive the pivot to permit the arm
- 20 to rock within the slotted portion of the V-shaped offset of the base, said base having a curved portion at one end with one end of the arm movable therebetween and connected to an electric circuit of an alarm, a contact
- 25 carried by and insulated from the arm and connected to the electric circuit of the alarm, a thermostat carried by the base, a forked member movable with the thermostat and receiving the arm to impart pivotal movement
- 30 thereto for engaging and disengaging the contact of said arm with the base, and a tension means between the arm and the base to urge said arm into engagement with the forked member.

35 In testimony whereof I affix my signature.
JOHN J. MACHACEK.
